UNITED STATES PATENT OFFICE

ROBERT J. HILL, OF CRANSTON, RHODE ISLAND, ASSIGNOR TO EAGLE PENCIL COMPANY,
OF NEW YORK, N. Y., A CORPORATION OF DELAWARE

DESIGN FOR A PENCIL CLIP OR SIMILAR ARTICLE

Application filed February 27, 1933. Serial No. 47,336. Term of patent 14 years.

To all whom it may concern:

Be it known that I, ROBERT J. HILL, a citizen of the United States of America, residing at No. 315 Auburn Street, Cranston, Rhode Island, have invented a new, original, and ornamental Design for a Pencil Clip or Similar Article, of which the following is a specification, reference being had to the accompanying drawing, forming part thereof, in which

Fig. 1 is a front elevation of a pencil clip or similar article showing my new design; and

Fig. 2 is a side elevational view thereof.

I claim:

The ornamental design for a pencil clip or similar article as shown.

ROBERT J. HILL.
